PROTECTIVE DEVICE

Robert Malcom, Jr., Chicago, Ill., assignor to
Chicago Eye Shield Company, Chicago, Ill., a
corporation of Illinois

Application July 28, 1950, Serial No. 176,400

7 Claims. (Cl. 2—8)

1

This invention relates to devices for protecting the head and face portion from injury by flying debris or particles such as are effected during the processes of welding, spray-painting, grinding, tool sharpening, metal cutting, sand blasting, and the like, and it relates more particularly to face masks or face shields.

This application is a continuation-in-part of my copending application, Serial No. 111,119, filed on August 19, 1949, and entitled "Face Shield," which application is now abandoned.

In present commercial practice the mask or face-shield portion of the device is usually provided in the form of a plastic sheet or the like which is secured at its rigid upper-end portion to a more rigid metal or fiber band so that the depending mask portion can project as a barrier in front of the wearer's face when in position of use. The supporting band is in turn pivoted at its ends to a head gear adapted to seat on the head of the wearer. The chief objection to constructions of this type of protection device resides in the fixed relation which usually exists between the mask portion and the head band. When so constructed, it is difficult if not impossible for the user to replace the mask or face shield with a new one when the old becomes unfit for the purpose for which it was intended. The shield portions cannot be interchanged easily so that the device is substantially inflexible and can be made suitably for only one general type of use. This requires a number of different structures to be stocked in order to have proper protection available for various operations that are carried out in production.

More important, the expansion characteristics of the materials of which the shield and the carrying band are formed are usually sufficiently different to set up strains under operating conditions which cause buckling and distortion of the more flexible face shield to the end that it often becomes unfit for the purpose for which it was intended.

When formed of plastic materials, such as cellophane, cellulose acetate, Pliolite, ethyl cellulose, methylmethacrylate or the like, materials which are subject to cold flow and even more sensitive thereto at elevated temperatures, deformation of the plastic sheet may occur such as cannot be compensated because of the rigid connection with the carrying band to the extent that buckling and distortion of the shield often results.

An object of this invention is to produce a protective device which is not subject to the objectionable features of the type described.

2

Another object is to produce a protective device having a face-shield member which may be easily and quickly mounted in its assembled relation on the supporting band and which may be as quickly and easily removed.

A further object is to produce a protective device of the type described in which the face shield is not mounted in fixed relation onto the supporting band but such relative movement is permitted as will compensate for cold flow of the material and differences in expansion of the materials without buckling or distortion of the parts.

A still further object is to produce a protective device of the type described in which the face-shield member can be quickly and easily interchanged to permit widespread use of the more expensive head gear with face shields of various types and sizes, which may be more easily stocked than the entire unit.

Another object is to provide a protective device of the type described in which the face-shield member is resiliently held in mounted relation but in which sufficient relative movement is permitted between the face-shield member and its support to nullify changes in dimension and to permit desirable adjustments with respect thereto.

In order to economize on the supply of protective devices stocked, it is advisable to have a head-gear unit which may be readily adjusted in size to fit various shapes and sizes of heads of the prospective wearers. Provisions for increasing or decreasing the head size of the head gear are not uncommon but it has been found that changes in dimension often cause modification of the angular relation of the head-gear members, which modification has been necessarily transmitted to the supporting band to the extent that either the head gear becomes uncomfortable to the wearer or else the changed angular relationship of the supporting band causes buckling or distortion of the face shield.

It is therefore a still further object of this invention to produce a device of the type described which automatically compensates for differences in size and shape of the head of the wearer.

A further object is to produce an improved protective device of the type described which is formed of relatively few simple parts that are easy to operate and adjust for effecting the desired mounted or unmounted relation, and in which the face-shield portion may be easily interchanged one with another to make best use of the device for particular operations.

These and other objects and advantages of this invention will hereinafter appear, and for purposes of illustration, but not of limitation, embodiments of the invention are shown in the accompanying drawings in which—

Figure 1 is a perspective view of one form of a protective device embodying features of this invention. Fig. 2 is an enlarged side elevational view partially in section of the device shown in Fig. 1. Fig. 3 is a sectional view taken substantially along the line 3—3 of Figure 2. Fig. 4 is a sectional view taken substantially along the line 4—4 of Fig. 1. Fig. 5 is a sectional view corresponding to that of Fig. 4 but showing a modified form of the invention. Fig. 6 is a sectional view similar to that of Fig. 4 showing a still further modification. Fig. 7 is a side elevational view of a protective device embodying a still further modification in the practice of this invention. Fig. 8 is a front elevational view of the protective device shown in Fig. 7. Fig. 9 is a sectional view taken substantially along the line 9—9 of Fig. 7. Fig. 10 is a sectional view taken substantially along the line 10—10 of Fig. 8. Fig. 11 is an enlarged perspective view of the face shield and band arrangement employed in the device shown in Fig. 7. Fig. 12 is an enlarged fragmentary view in side elevation of the device shown in Fig. 1. Fig. 13 is a sectional elevational view taken substantially along the line 13—13 of Fig. 12. Fig. 14 is a sectional elevational view taken substantially along the line 14—14 of Fig. 13. Fig. 15 is a perspective view of a modified form of face shield which may be used in the practice of this invention. Fig. 16 is a sectional view taken along the line 16—16 of Fig. 15.

The face shield embodying features of this invention is indicated by the numeral 10. It includes a head gear for positioning the device on the head of the wearer. The head gear may consist of a head band 11 provided at its overlapping rearward end portions with slots 12, the overlapping ends being slidable in a curvilinear sleeve 13. A bolt 14 and nut 15 operate through an intermediate portion of the sleeve for clamping the overlapping ends of the head band 11 in their adjusted relation within the sleeve 13 whereby the head band may be dimensioned to correspond to the particular head size of the wearer. A transverse head piece 16 may be secured at its ends to the head band 11, as by a number of spaced rivets 17, for the purpose of providing contact over the cranium portion for comfortably locating the head gear on the head of the wearer. A pair of inverted U-shaped connecting elements, which will hereinafter be described in greater detail, are also secured to the head band 11 by the rivet members 17.

The head gear may also have a protective shield portion 20 formed of relatively rigid material and having a depending flanged portion 21a which is adapted to mount a curvilinear face-shield supporting band 21 fixed thereto, as by rivets 22. It will be understood that the band member 21 may be formed as a part of the flanged portion 21a. The band 21 forms a relatively rigid curved support that is adapted to overlie the forehead portion of the wearer when in position of use, that is, when the head band of the head gear is rocked to a lowered position of adjustment. The supporting band 21 is also provided with a bracket 23 in the form of a depending flanged member for carrying a spring-pressed ball-and-socket joint 24 which permits the head band to be rocked

between raised and lowered positions of adjustment.

The supporting band 21 is provided in its outer surface with a longitudinal recessed or grooved portion 26 which is adapted to receive projections in the form of buttons 27 formed in the upper edge portion of a face-shield member 28. The shield 28 is preferably formed of transparent material which is somewhat flexible, such as from plastic sheet stock or wire screening, as will hereinafter be described. The groove or recess 26 and the buttons 27 form interengaging parts which are adapted to locate the face shield 28 in position of use on the outer surface of the support 21 but in such manner as will permit sliding movement of the buttons laterally within the groove to compensate for differences in expansion between the material of which the face shield is formed and the material of which the supporting band is formed. Such slideable interconnection between the face shield and the band also permits lateral adjustment of the face shield relative to the head gear for various purposes and to meet various circumstances which may arise in use.

As previously described, the bracket 23 is formed of an extension of the band 21 and another piece of relatively rigid sheet stock 23a. The two are fixed together in juxtaposed relation by flanges 23b which are turned in from the edge portions of the added piece to engage the opposite walls of the extension from the band 21, as illustrated in Fig. 3. A central portion of the juxtaposed members are spread apart, as shown at 30, to form an internal cavity 31 which opens forwardly through a reduced opening 32. A spring 33 is located within the cavity 31. The forward end of the spring bears against the forward end of the cavity having the reduced opening 32 while the other end of the spring bears against a washer 34 which seats on the end of a band or wire 35 which extends outwardly through the reduced opening 32. The band 35 overlies and is adapted operatively to engage the outer surface of the upper edge portion of the face shield 28. The opposite end of the band 35 may be similarly anchored within another cavity 36 formed on the opposite portion of the supporting band 21. In this manner, the band or wire 35 is constantly stretched in the endwise direction and establishes resilient engagement with the outer wall of the band 21 or face shield member 28, when in position of use, and whereby the face shield may be held in place on the curved supporting band 21. Described more specifically, the wire 35 and spring members 33 provide a resilient member which constantly urges the face shield against the supporting band thereby to maintain resilient interengagement between the parts when the buttons of the face shield are positioned within the recess of the supporting band. Such resilient engagement permits relative sidewise movement between the parts to prevent buckling or distortion of the face shield, as would otherwise be effected because of expansions or cold flow in prior systems.

For the purpose of adjusting the band 35 into and out of the grooved portions described, a clip member 38 is provided which is slideable thereon and has a finger-gripping portion to facilitate operation thereof.

In the form of the invention illustrated in Figure 5, the face shield is designated by the numeral 40 and each of the projections operating within the longitudinal recess 26 of the curved supporting band 21 is in the form of a longitudinal pro-

jection 41 formed integrally in the upper margin of the shield. Such projection may be in the form of a continuous projection, as shown, or it may constitute a number of laterally spaced apart projections adapted to operate within the recess 26, when in the assembled relation. When in the form of a continuous projection that seats within the recess, the wire 35, forming the flexible band, is adapted to fit within the projection 41 to urge the shield 40 in clamping relation in place on the curved supporting band 41 while permitting relative lateral movement between the support and the shield.

The form of the invention illustrated in Figure 6 is similar to that of Figure 5 except that the assembly includes a curvilinear strip 45 having a projection 46 which corresponds to and is received within the projection 41 of the face shield. Substantially the same results are obtained by this arrangement except that the wire or band 34 is received in the recess formed by the projections 46 to press the strip 45 against the face shield 40 which, in turn, presses the projections 41 of the face shield into operative engagement with the recess 26 of the supporting band. Each of the elements described in this modification are able to move endwise relative to each other.

In the form of the invention illustrated in Figures 7 to 11 inclusive, the curved supporting band 21 is provided with a guiding ridge 50 and carries a plurality of pins 51, such as the three shown in laterally spaced apart relation. The curved supporting band 21 is provided with a pair of horizontally disposed keyhole slots 52 near its ends. The shield member is here designated by the numeral 53. The upper edge portion of the shield 53, which is adapted to engage the outer surface of the curved supporting band 21, is provided with keyhole slots 54 that correspond generally with the keyhole slots 52 in the band 21; a pair of elongate slots 55 through which the pins 51 disposed on each side of the center pin are adapted to extend when in the assembled relation, and an opening 56 through which the center pin 51 extends in substantially fitting relation. The band for holding the shield in place on the curved support, which is designated by the numeral 57, is formed with a pair of keyhole slots 58 which correspond generally to the keyhole slots 52 and 54, a pair of elongate slots 59 which correspond to the slots 55 in the shield and an opening 60 through which the central pin 51 extends.

Each bracket 23 of the supporting band 21 is provided with a boss 62 for accommodating a coil spring 63 or other resilient member. One end of the spring 63 is secured to the rear wall of the boss 62 while the other end is fixed to a link 64 that extends outwardly through the suitable opening in the boss. The forward end of the link 64 is provided with a flange which forms a finger grip 65 for adjusting the link endwise against the tension of the spring 63, and it is also provided with a headed pin 66 that is adapted to extend through the registered keyhole slots 58, 54 and 52 formed in the band, the shield and the curved supporting band respectively. When the pin 66 is engaged in the keyhole slots, as illustrated in Figure 9, the band 57 constantly urges and resiliently clamps the shield 53 in place on the curved support. Although the parts described are incapable of relative movement because of the fixed relation established at their center by the center pin 51, relative endwise adjustment of the associated parts to compensate for cold

flow or for differences in thermal expansion is permitted since the other pins 51 extend through slotted portions 55 and 59. The extent of adjustment between the parts is necessarily limited by engagement of the pin with the ends of the slots; however, these are designed to permit the movement necessary under the expansion and cold flow which takes place without causing buckling or distortion of the parts. To remove the shield from the curved support, the headed pin 66 is removed from the keyhole slots whereby the force of the spring constantly urging the parts into engagement is relieved. The band 57 may then be removed and the shield lifted off of the pins 51.

Instead of forming the face shield of a plastic member having a recess or offset portions in the upper end for establishing sliding engagement with the recess across the positioning band 21, the face shield may be in the form of a metal screen 70 or the like, such as illustrated in Figure 15. In such modification, the upper edge portion of the screen 70 is fixed, as by rivets 71, to a resilient band 72 of relatively rigid material having a recess or projection 73 of the type heretofore described for establishing operative sliding engagement with the recess 26 provided in the supporting head band 21. Instead of a screen member, which is particularly well adapted for use as a spark shield, other metallic, plastic, or fabric sheets may be used in various sizes. Such modified shield members need not be transparent throughout their entire area as opaque shields may be formed with glass, plastic or screenlike windows in the shield member at eye level for vision therethrough.

Figures 12 to 14 inclusive are detail views showing the connection between the head gear and the supporting band 82 which provides for automatic adjustment for retaining proper angular relation of the parts notwithstanding adjustment of the head gear or modification of its angular position as occasioned by fitting the head gear to the contour of the head portion of the person upon which the gear sits when in position of use.

As shown, the connector is in the form of an inverted U-shaped strip 80 one end of which is fixed, as by laterally spaced rivets 81, to the adjustable head band 82 which encircles the head and the curvilinear upwardly extending band portion 83 which passes over the cranium of the wearer. The free end portion 84 of the connector strip 80 is laterally offset and is secured, as by a rivet 85 or the like, to a ball member 86 which is freely rotatable in all directions within a ball socket 87 formed by the inner and outer juxtaposed strips 88 and 89, which correspond to the elements 21 and 23 heretofore described. The inner strip 89 is secured in position by downturned end portions 90 of the outer strip 88. The inner strip 89 forms a part of the supporting band 21, heretofore described.

Thus, when the head gear is adjusted for size and tilted to correspond better to the curvature of the head of the wearer, relative tilting and turning movement is permitted between the supporting band and the head gear so that the desired angular relation of the supporting band and the face shield may be retained and buckling of the face shield thereby prevented.

In this manner, the protective device can be easily and quickly adapted for use by persons having widely differing head sizes and shapes without the device becoming uncomfortable and without placing such strain upon the parts as will dis-

tort or buckle the face shield or make the unit unfit for the purpose for which it was intended.

In accordance with this invention, face shields of various sizes, shapes and materials may be quickly and easily replaced or interchanged one for another thereby to adapt the device for a wide number of uses so that more efficient and more effective use can be made of a single unit.

It will be understood that instead of forming the recess in the supporting band for operative engagement by buttons or projections in the face shield member, the supporting band may be provided with such buttons or projections while the face shield member is formed with the receiving recess or recesses to establish the desired operative engagement.

It will be further understood that numerous changes may be made in the details of construction, arrangement and operation without departing from the spirit of the invention, especially as defined in the following claims.

I claim:

1. In a protective device of the type described, a curvilinear support which overlies the forehead of the wearer when in position of use, a face shield adapted to be rocked with the support between raised and lowered positions of adjustment whereby the face shield provides a protective barrier in front of the face of the wearer when in lowered position of adjustment, interengaging portions on the support and the upper edge portion of the face shield including an elongate recess in one and a projection in the other whereby the face shield is located on the support in a manner to militate against relative up and down movement while permitting relative endwise movement when the projections are seated within the recess, and means on said support for constantly urging said interengaging portions into operative engagement when in position of use thereby resiliently to establish the assembled relation.

2. In a face shield, a relatively rigid curved support adapted to overlie the forehead of the wearer, a relatively flexible shield having its upper margin engaging the outer surface of the curved support and adapted to overlie the face of the wearer, interengaging parts on the support and shield for locating the shield in place on the support but allowing relative longitudinal movement of the support and shield, and a resilient band secured at its ends to the support and engaging the outer surface of the upper margin of the shield for resiliently clamping the shield in place on the support.

3. In a face shield, a relatively rigid curved support adapted to overlie the forehead of the wearer, a relatively flexible shield having its upper margin engaging the outer surface of the curved support and adapted to overlie the face of the wearer, recess means extending along the outer surface of the curved support, projection means in the upper margin of the shield engaging in the recess means of the support for locating the shield in place on the support but allowing relative longitudinal movement of the support and shield, and a resilient band secured at its ends to the support and engaging the outer surface of the upper margin of the shield for resiliently clamping the shield in place on the support.

4. In a face shield, a relatively rigid curved support adapted to overlie the forehead of the

wearer, a relatively flexible shield having its upper margin engaging the outer surface of the curved support and adapted to overlie the face of the wearer, a recess extending longitudinally along the outer surface of the curved support, projections extending along the upper margin of the shield and engaging in the recess of the support for locating the shield in place on the support but allowing relative longitudinal movement of the support and shield, and a resilient band secured at its ends to the support and engaging the outer surface of the upper margin of the shield for resiliently clamping the shield in place on the support.

5. In a face shield, a relatively rigid curved support adapted to overlie the forehead of the wearer, a relatively flexible shield having its upper margin engaging the outer surface of the curved support and adapted to overlie the face of the wearer, a recess extending longitudinally along the outer surface of the curved support, a projection extending longitudinally along the upper margin of the shield and engaging in the recess of the support for locating the shield in place on the support but allowing relative longitudinal movement of the support and shield, and a resilient band secured at its ends to the support and engaging the outer surface of the upper margin of the shield for resiliently clamping the shield in place on the support.

6. In a face shield, a relatively rigid curved support adapted to overlie the forehead of the wearer, a relatively flexible shield having its upper margin engaging the outer surface of the curved support and adapted to overlie the face of the wearer, interengaging parts on the support and shield for locating the shield in place on the support but allowing relative longitudinal movement of the support and shield, a band engaging the outer surface of the upper margin of the shield, and resilient means for securing the ends of the band to the support for resiliently clamping the shield in place on the support, and a clip slidably longitudinally along the band for lifting the band from the outer surface of the shield to permit removal of the shield from the support.

7. In a face shield, a relatively rigid curved support adapted to overlie the forehead of the wearer, a relatively flexible shield having its upper margin engaging the outer surface of the curved support and adapted to overlie the face of the wearer, a band engaging the outer surface of the upper margin of the shield, interengaging parts on the support and shield for locating the shield in place on the support but allowing relative longitudinal movement of the support and shield, and a clip slidably longitudinally along the band for lifting the band from the outer surface of the shield to permit removal of the shield from the support.
